HIGH TENSION INSULATOR

Filed Oct. 5, 1926

UNITED STATES PATENT OFFICE

PHILIP B. STEWART, OF CINCINNATI, OHIO

HIGH-TENSION INSULATOR

Application filed October 5, 1926. Serial No. 139,733.

My invention relates to the provision of means in addition to the insulators employed with high tension electrical transmission lines for clearing flash overs from the lines, from 5 various causes, thereby eliminating outages to the circuit, and damage to the line.

The theory of my invention is to provide a suitable gap across the insulator in series with a fuse, which is capable of interrupting 10 the current of the line to ground.

The invention is arranged for use on an insulator of a type used for high tension transmission lines, wherein a string of insulators serve to support the transmission wire. A 15 metal grading ring is preferably used to define a path of discharge, which metal ring is attached to the string of insulators at an intermediate point. I then employ a fuse which is located between the transmission conductor 20 and the grading ring.

There are various possible arrangements, and I will describe a specific construction whereby I accomplish my objects, it being understood that the specific construction is 25 exemplary only of my invention, and embodies the preferred form thereof. I will set forth the novelty inherent in my invention in the appended claims.

In the drawings:—

30 Figure 1 is a side elevation of the device complete.

Figure 2 is a detail of one of the upper horns.

35 Figure 3 is a detail of half of the grading ring.

Figure 4 is a detail of one half of the supporting clamp for the grading ring.

I have shown a series of insulators 1, joined 40 together in the usual manner. The clamp 2, which serves to support the transmission wire 3 on the insulator, is of regular type, and to it is bolted the fuse arm 4, which is thus in electrical contact with the line.

At some suitable space above the cable or 45 line support, a pair of clamp plates 5, having arms 6, are bolted together around one of the insulators. Secured to one of the clamp arms is a fuse clip 7, and secured to the fuse arm 4 is secured a fuse clip 8. The fuse 9 is set between the clips.

Secured to the arms 6 are the two loops or half rings 10, which when erected, extend on both sides of and surround the insulator.

Secured near the upper end of the insulator string are the horns 11, which have curved 55 portions 12, that are set around the body of the upper insulator, and bolted together about the insulator.

In case of a discharge of lightning or some sudden surge discharge in the line, the tendency to flash-over will take a path through the fuse to the grading ring formed by the two half rings 10, and from the grading ring to the horns across the air gap, this being easier than a path directly through the insulator string or closely in line with it.

However, the fuse which carries the current to the grading ring will blow and break the path of discharge to the grading ring, thus avoiding an interruption of service to 70 the circuit and damage to other parts of the line. When the fuse blows, it will not in any way interfere with the regular functioning of the insulators, and it will be easy for the line-men to see blown fuses in their regular inspections which are made from the ground with field glasses as a regular practice at the present time.

Some other sort of gap could be provided, and the mechanical structure described replaced with some equivalent structure, so long as a gap across the insulator is provided in series with a fuse for interrupting the current from the line to ground.

Having thus described my invention, what I claim as new and desire to secure by Letters Patent, is:—

1. An insulator device comprising an insulator, means creating a path for flash-overs across the insulator so as to short the insulator, and a fuse arranged in series with the said path, and a conductor supported by the insulator and connected to said fuse.

2. An insulator device comprising a string 95 of insulators, means intermediate the ends of the string providing a path for flash-overs across the insulator, an electric conductor supported by said insulators beyond the flash-over path, and a fuse forming the only 100

direct path from said conductor to the said intermediate flash-over means.

3. An insulator device comprising a string of insulators, a grading ring mounted on the insulators intermediate the ends of the string, an electric conductor supported on one end of the string, and a fuse from the electric conductor to the grading ring.

4. An insulator device comprising an insulator, means creating a path for flash-overs across the insulator, and a fuse arranged in series with the said path, said fuse being long enough to avoid easy flash over around the fuse in case of a surge discharge from the line, and being directly connected with the conductor.

5. The combination with a string of insulators for suspending a conductor from a stationary support, of electrode means carried by the intermediate portion of the string of insulators for providing a flash-over path at one side thereof, and a fuse connected with the conductor interposed in series with said path and adapted to be blown upon the occurrence of a flash-over for extinguishing the arc.

6. In combination with a string of insulators for suspending a conductor from a stationary support, protective means for the string comprising electrodes carried thereby in spaced and insulated relation to the support and providing an air gap adapted to be jumped by an arc in the event of a flash-over, and means arranged in series with the gap and connected with the conductor for extinguishing the arc in the event of a flash-over.

7. In combination with an insulator mechanically connected with a high tension conductor, protective means comprising electrodes carried by the insulator and providing a flash-over path for an arc resulting from a sudden electrical surge in the line, and means interposed in series with said path and connected with the conductor for disrupting an arc.

45 PHILIP B. STEWART.
